GARMENT CREASER

Joseph J. Nugent, Thornwood, N. Y.

Application October 19, 1932. Serial No. 638,638

3 Claims. (Cl. 223—19)

This invention relates to garment creasers, and its general object is to provide a creasing device primarily designed for trousers that includes telescopically mounted members made up into sections, one for the front portion of the legs, and the other for the rear portion thereof, and the front section is of a size to telescopically receive the rear section, when the device is not in use, therefore the device can be folded to permit it to be packed in minimum space, yet when open and disposed in trousers will crease the latter in a manner whereby the crease will last for a long period of time.

Another object of the invention is to provide a garment creaser that can be easily and expeditiously applied and removed with respect to a pair of trousers and only a part of the creaser can be used if desired, as a creasing means, as well as a hanger for the trousers.

A further object of the invention is to provide a sectional trousers creaser, with a suspending hook on one section, arranged so that the trousers are held in a true vertical position and the sections are associated with respect to each other in a manner whereby the combined weight of the trousers and creaser will cause the sections to separate and set up pressure against the trousers' legs to bring about the creasing action.

A still further object of the invention is to provide a garment creaser of the character set forth, that is simple in construction, inexpensive to manufacture, easy to use, and extremely efficient in operation and service.

This invention also consists in certain other features of construction and in the combination and arrangement of the several parts, to be hereinafter fully described, illustrated in the accompanying drawing and specifically pointed out in the appended claims.

In describing my invention in detail, reference will be had to the accompanying drawing wherein like characters denote like or corresponding parts throughout the several views, and in 45 which:

Figure 1 is a view illustrating my creaser in use.

Figure 2 is a front view of the creaser per se.

Figure 3 is a similar view of the creaser completely folded.

Figure 4 is a view of the rear section folded.

Figure 5 is a sectional view taken approximately on line 5—5 of Figure 1, looking in the direction of the arrows.

Figure 6 is a sectional view taken approxi-

mately on line 6—6 of Figure 3, looking in the direction of the arrows.

Figure 7 is a fragmentary view of the curved end of the rear section to illustrate the latching means for the telescopically mounted members.

Figure 8 is a sectional view taken approximately on line 8—8 of Figure 7.

Figure 9 is a sectional view taken approximately on line 9—9 of Figure 7.

Figure 10 is a fragmentary view illustrating the arrangement of the ball receiving sockets in the arms of the body member of the device.

Referring to the drawing in detail, the letter A indicates a pair of trousers to illustrate the use of my creaser which includes what I term a front section and a rear section.

Each of the sections are substantially U-shape in configuration, and the front section includes a body member 1 that is substantially V-shape in cross section as best shown in Figure 5 to provide channel arms having substantially sharp outer edges 2 that provide the creasing means for the body members, while telescopically mounted in the arms of the body members are auxiliary creasing members 3 which are V-shape in cross section and are shaped to fit within the arms as clearly shown in Figure 5. The arms of the body members are provided with inwardly extending flanges 4 that are arranged in opposed

relation with respect to the outer wall of the arms and the inner edges of the flanges engage the outer edges of the auxiliary creasing members to set up a frictional action against the same so as to hold the auxiliary members associated with the arms when the auxiliary members are extended as best shown in Figure 1.

The rear section likewise includes a body member 5 that is provided with substantially V-shape in cross section arms forming channels which may have arranged therein filler members 6 and telescopically mounted in the arms of the body member 5 are auxiliary creasing members 7 which are likewise V-shape in cross section and the outer edges of the auxiliary creasing members cooperate with the outer edges of the arms of the body member 5 to crease the rear portions of the legs as best shown in Figure 1.

Arranged in the eight portions of each of the body members 1 and 5 is a latching means for the auxiliary members, and each latching means includes a pair of arcuate shaped dogs 8 that are pivotally mounted on pins 9 and have formed on one of their ends, hooks 10 which are adapted to be received in notches 11 arranged in the upper ends of the auxiliary members as best

shown in Figure 8. The bight portion of each of the body members has arranged therein an opening through which extends a button 12 that is engageable with the opposite ends of its pair 5 of dogs 8 as best shown in Figure 7, to actuate same against the tension of a coil spring 13. By this construction, it will be apparent that when the auxiliary members are arranged in their innermost positions, the hooks 10 will automatically be disposed in the notches 11 for securing the auxiliary members in their folded position as illustrated in Figure 8. However, when the buttons are pressed, the hooks are released from the notches so that the auxiliary 15 members can be arranged to their open position as shown in Figures 1 and 2.

The filler members 6 are provided with longitudinally arranged slots disposed in the outer faces thereof, and bridging the slots are pins 14 which have pivotally secured thereto one of the ends of cross rods 15 that are disposed in parallel pairs as suggested in Figure 5, and secured to the free ends of the cross rods 15 are balls 16 which are of a size to fit into sockets 16' arranged in the confronting faces of the outer ends of the inwardly extending flanges 4 of the arms of the body member 1, as clearly shown in Figure 5, otherwise there is no connection between the respective front and rear sections.

Secured to the arms of the body member 1 adjacent the bight portion thereof as best shown in Figure 3, is a suspending member 17 which is formed from twisted wire and extends upwardly at a rearward inclination from the arms as best shown in Figure 1. The suspending member is provided with a convolution intermediate its ends and thence terminates into a hook 18 that is adapted to be arranged in a line substantially midway between the respective sections so that when the sections are disposed in a pair of trousers, the trousers will hang in a true vertical plane, and due to the combined weight of the creaser and the trousers, it will be obvious that pressure will be applied to the rear section from the front section through the medium of the cross rods 15 which have the balls thereof engageable with the front sections as best shown in Figure 5, and thereby have a tendency to separate the sections to set up the creasing action.

In the use of my creaser the sections are disposed within the respective legs of a pair of trousers as shown in Figure 1, and the rods are then disposed so that the balls thereof are received in the sockets 16' of the front section. The auxiliary members are released by pressing upon the buttons 12, and moved to the extended position. The device together with the trousers are then hung on a suitable supporting means through the medium of the suspending means to bring about the creasing action.

65

70

75

The reverse action from that just described takes place when the device is removed from the trousers, and as the front section is of a size to accommodate the rear section, the arms of the rear section are telescopically mounted in the arms of the front section when it is desired to fold the device, and when so folded as shown in Figure 3, it will be apparent that the device can be packed in minimum space, and can be conveniently carried in a hand bag or the like.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A garment creaser comprising a pair of substantially U-shaped sections, each section including a body member having parallel arms, auxiliary members telescopically mounted in the parallel arms, said arms and auxiliary members having creasing edges, means pivotally secured to one of said sections and detachably received by the other section for associating the sections together in a garment, and a suspending means secured to one section.

2. A garment creaser comprising a pair of substantially U-shaped sections, each section including a body member having parallel arms, auxiliary members telescopically mounted in the arms and together with the arms having creasing edges, rods pivotally mounted to one of said sections and received by the other section for associating the creaser in a garment, suspending means for the creaser and one of said sections being of a size to telescopically receive the other section for disposing the creaser in folded position.

3. A garment creaser comprising a pair of sections, each section including a body member having parallel arms provided with channels, auxiliary members telescopically mounted in the channels, latching means for holding the auxiliary members in their innermost position, said arms and auxiliary members having creasing edges, rods for associating the sections in cooperative relation with respect to each other in a garment and carried by one of said sections for detachable connection with the other section, and a suspending means carried by the last mentioned section and arranged whereby the weight of the creaser and garment will set up a pressure between the section carrying the suspending means and the other section through the medium of the rods to separate the sections to bring about the creasing action.

JOSEPH J. NUGENT.
